The ornamental design for a support member for a vehicle carrier, as shown and described.

DESCRIPTION

FIG. 1 is a perspective view of a support member for a vehicle article carrier showing my new design;

FIG. 2 is an enlarged view of the support member for a vehicle article carrier shown in FIG. 1;

FIG. 3 is a top view thereof;

FIG. 4 is a rear view thereof;

FIG. 5 is a right side view thereof;

FIG. 6 is a front view thereof; and,

FIG. 7 is a left side view thereof.

The broken lines in FIG. 1 are meant to indicate a cross bar coupled to the support member, a slat upon which the support member rests and a portion of an outer body surface of a vehicle, none of which form any part of the claimed design of the support member.
